DESIGN FOR A COMBINED EYE SHADOW
AND ROUGE CASE

Elizabeth N. Graham, New York, N. Y.

Application July 22, 1947, Serial No. 140,454

Term of patent 14 years

(Cl. D86—10)

To all whom it may concern:
Be it known that I, Elizabeth N. Graham, a citizen of the United States of America, residing in New York city, county of New York, and State of New York, have invented a new, original, and ornamental Design for a Combined Eye Shadow and Rouge Case, of which the following is a specification, reference being had to the accompanying drawing, forming part thereof, wherein,

The sides and rear of the combined eye shadow and rouge case are identical to the front shown in Figure 1.

I claim:

The ornamental design for a combined eye shadow and rouge case, substantially as shown and described.

ELIZABETH N. GRAHAM.
